DESIGN FOR A READING LENS OR THE LIKE

George M. Cressaty, New York, N. Y.

Application November 22, 1944, Serial No. 116,498

Term of patent 14 years

(Cl. D57—1)

To all whom it may concern:

Be it known that I, George M. Cressaty, a citizen of France and residing at New York, in the county and State of New York, have invented a new, original, and ornamental Design for a Reading Lens or the like, of which the following is a specification, reference being had to the accompanying drawing forming part thereof:

Fig. 1 is a front elevational view of a reading lens or the like showing my new design;

Fig. 2 is a rear elevational view thereof;
Fig. 3 is an end elevational view of the same,
and

Fig. 4 is a transverse sectional view thereof
taken along the line 4—4 of Fig. 1.

I claim:

The ornamental design for a reading lens or
the like, substantially as shown.

GEORGE M. CRESSATY.
